UNITED STATES PATENT OFFICE

ISRAEL W. COOPER, OF NEW YORK, N. Y.

SPRING CLIP FOR ORNAMENTS AND THE LIKE

Application filed December 29, 1931. Serial No. 583,722.

This invention relates to detachable ornaments and more specifically to the means by which such ornaments may be affixed to portions of feminine apparel such as coats, dresses, hats and shoes.

A main object of the invention is to provide an attaching means or clip for an ornament of this kind, which is particularly adapted for feminine use in that no mechanical skill whatever is required for affixing it to a garment.

A further object is the provision in such a clip of tension means which cannot be strained beyond its point of elasticity.

Another object is to provide for such an ornament, an affixing or gripping member made entirely of one piece and which with the ornament proper, combines to form a simple two piece structure requiring no hinge pins or separate springs.

A further object is to provide on the ornament to which the clip is to be attached, an integral lug formed with means to mount the clip, said means being provided with an angled top surface which serves to positively limit the movement of the gripping member or clip when opened, so that the tension spring may not be unduly strained.

Other useful objects will become apparent from the following specifications which describes the attending drawing and which illustrates a preferred embodiment of the invention and in which:

Fig. 1 is illustrative of a rear view of an ornament provided with gripping means or clip in accordance with the invention.

Fig. 2 illustrates a side view thereof as used, and

Fig. 3 shows a vertical sectional view as taken along the line 3—3 of Fig. 1, with the gripping member in its outermost position.

Referring to the drawing in greater detail, there is shown at 5 the rear side of an ornament 6 which is of generally well known construction. It is usually a casting of soft white metal set with rhinestones. In this instance it is preferred that a bifurcated lug 7 be integrally cast with the ornament 6 and that the lug be provided with a bridge-like member 8.

The gripping member or clip 9 is preferably made of thin but fairly rigid metal stock capable of being formed in punching and forming dies. Speed from the longitudinal margins of the member 9, slits 10 may be made forming a central tab 11 and two adjacent tines 12 which are curved to produce resilient members as shown. 55

From the center of the tab 11 there is preferably punched a tongue 13 which may be readily bent around the bridge 8 forming a hinge to unite for articulation the ornament 6 with the gripping member 9. 60

At its free end the member 9 is preferably provided with a gripping prong or prongs 14 65 for coaction with a portion of a garment such as is shown at 15.

The spring tines 12 are bent or curved to such a degree that when their ends and the prongs 14 all bear against the rear side 5 of 70 the ornament no looseness between the ornament and gripping member will be apparent, i. e., the springs 12 will be under slight tension. It is desirable therefore that the springs 12 impinge against the ornament on 75 the side of the lug 7 opposite from where the prongs 14 impinge. It is apparent then that the prongs 14 may be removed from contact with the rear side of the ornament to permit insertion of a portion of a garment between 80 the ornament and the gripping member by applying pressure against the end of the tab 11, which serves as a finger piece and as the ends of the springs 12 are firmly impinged against the ornament, the springs will be 85 further tensioned as indicated in Fig. 3. When the pressure is released from the tab 11 the gripping member will assume the position shown in Fig. 2 with the prongs 14 pressing into the garment and the springs 12 in tension. 90

The lug 7 is preferably provided with a flat, slightly angled top 16 for engagement with the under face of the tab 11. The degree of this angle will determine the amount of separation between the ornament and the gripping member and the flat to flat engagement between the top 16 of the lug and the under face of the tab 11 will prevent undue straining of the springs 12. 95

The foregoing disclosure is to be regarded 100

as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters

10 Patent, is:

1. Means for detachably affixing an ornament to a garment comprising an ornament having an integral lug provided with a bridge, a gripping member hingedly engaged with the bridge, spring members integrally formed at one end of the gripping member, prongs formed at the other, said spring members and prongs arranged to impinge upon the rear face of the ornament on opposite sides of the lug and an operating tab integral with the gripping member.
2. The combination with a detachable ornament having a hinge pintle integral therewith, of a gripping member for a detachable ornament comprising a body portion having hinge means engageable with the pintle on the ornament, an operating tab disposed at one end of the body portion, curved springs on each side of the tab and co-extensive thereon and prongs on the other end of the body portion.
3. A removably attachable garment ornament, comprising a cast ornament member having an integral hinge lug, a gripping member having an integral hinge member engageable with the hinge lug, to spring members integral with the gripping member arranged to impinge against the rear of the ornament member and below the hinge lug and an elongated portion of the gripping member arranged to impinge the rear of the ornament above the hinge lug, and an angled top on the hinge lug engageable with a portion of the gripping member to limit its movement and to prevent undue straining of the spring members.

Signed at New York, in the county and State of New York, this 28th day of December, 1931.

50 ISRAEL W. COOPER
